UNITED STATES PATENT OFFICE.

EDWARD W. BURKE, OF ROCKVILLE, CONNECTICUT, ASSIGNOR TO UNITED STATES ENVELOPE COMPANY, OF SPRINGFIELD, MASSACHUSETTS, A CORPORATION OF MAINE.

TWO-COMPARTMENT ENVELOPE.

Application filed December 26, 1922. Serial No. 608,965.

The present invention relates to envelopes for mailing purposes, and more particularly to those which provide, in a single unitary structure, two separate compartments, the purpose being to provide a double or duplex envelope for the transmission by mail to the same address of two different classes of postal matter, mailable at different rates of postage.

10 The invention contemplates an envelope structure providing a compartment or pocket of large size to receive bulky matter, such as merchandise, catalogues, and the like, which are mailable at a low postal rate, and integral therewith, and within the area of said large compartment, a smaller compartment or pocket, capable of being securely sealed, and adapted to contain the invoice, bill, letter, or the like, which, though mailable only at a higher postal rate, it is desired to transmit with the bulky matter, under one and the same address. According to the invention, such a two compartment envelope structure is susceptible of formation from a single sheet or blank, and withal, under such simple requirements for gumming, folding and sealing, as to render quantity production entirely feasible by the automatic machines which are employed in the manufacture of standard envelopes. These and other advantageous features of the invention will hereinafter more fully appear, reference being had to the accompanying drawings, in which—

35 Fig. 1 shows a two compartment envelope constructed in accordance with the invention.

Fig. 2 shows a blank, in flat or extended position, before folding, from which the envelope of Fig. 1 is made.

40 Fig. 3 shows the envelope on a smaller scale, in readiness for mailing and with postage affixed to the two compartments.

Like reference characters refer to like parts in the different figures.

45 Referring first to Fig. 2, the envelope blank provides a body portion 1, constituting, when the blank is folded, the unseamed face or, as it is sometimes called, the front portion of the envelope. At the ends of the portion 1 are the flaps 2 and 3, the last named being gummed, as shown at 4, to provide, when folded, the bottom seam of the larger compartment. One wall of this larger com-

partment is constituted by the body or unseamed front portion 1, and the opposite wall by a flap or back portion 5, which is folded over on the broken line 6 in advance of the folding on broken line 7 of an opposite side flap or supplemental back portion 8.

55 The flap 5 is substantially coextensive with the body portion 1, and hence when folded over on the broken line 6, it is overlapped and partially covered by the flap 8, the latter, along its edge, having longitudinally spaced portions 9 and 10 which adhere to the flap 5 to form, in effect, a longitudinally center seam for the larger compartment. The adhesion of flap 3, when folded over upon the flaps 5 and 8, provides the bottom 60 seam for the large compartment, and the closure for said large compartment, namely the flap 2, may be used in any manner desired to retain in said compartment the bulky 65 postal matter for which said compartment is intended.

70 In addition to the edgewise adhesion provided by the spaced gummed portions 9 and 10, the flap 8 is secured to the flap 5 by the spaced transverse gummed portions 11 and 12, the latter providing, in effect, the end 75 seams of a smaller compartment or pocket whose rear and front walls, respectively, are constituted by the overlapping matching portions of the flaps 5 and 8 as included between the adhesion surfaces 11 and 12. Access to this smaller pocket is had by way 80 of the longitudinal gap, along the edge of flap 8, between the gummed portions 9 and 10,—there being provided, coextensive with 85 this gap, a sealing extension 13 which is gummed along its edge, as shown at 14. The letter, invoice, or other postal matter which is mailable at a higher rate of postage 90 is insertible, as shown in Fig. 1, through this gap, so as to lie between the flaps 5 and 8 in the space defined by the gummed portions 11 and 12,—and if so 95 desired, said inclosure may be so folded 100 that the address thereon will be disclosed through a window opening or transparency 105 15 which may be formed in that part of the flap 8 which constitutes the outer wall of the smaller pocket. Said smaller pocket may then be closed and sealed by moistening and pressing down the gummed edge 14 of projection 13, it being noted in this connec-

tion that all of the gumming of the blank, for the manufacture of the two compartment structure and for the sealing of same in actual use, is confined to one side or face of the blank.

After sealing as above described, the envelope structure, with its two classes of postal matter separately inclosed, is then ready for mailing, as shown in Fig. 3, upon the placing of the correct postage, for the higher and lower rates respectively, on the small and large compartments, as indicated at 16 and 17.

I claim:

- 15 1. A duplex envelope formed of a single piece of material having a front portion, a main back portion folded over on to said front portion, a supplemental back portion folded over on to said main back portion and connected to said back portion but free therefrom for a portion of its length, whereby a compartment is formed between said back portions of the depth of said supplemental portion with an opening for the mail matter, and a sealing flap on said supplemental back portion at its free portion adapted to be connected to said main back portion.
- 20 2. A duplex envelope formed of a single piece of material having a front portion, a main back portion folded over on to said front portion, a supplemental back portion folded over on to said main back portion, the opposite end portions of said supplemental back portion being connected to said main back portion, the intermediate portion of said supplemental back portion being free, whereby a compartment is formed between said back portions of the depth of
- 25 30 35 40 said supplemental portion with an opening for the mail matter, and a sealing flap on said supplemental back portion at its inter-

mediate portion adapted to be connected to said main back portion.

3. A duplex envelope formed from a one-piece blank or sheet, the latter consisting of two rectangular portions folded one upon the other to constitute the opposite walls of one compartment, and also consisting of a third rectangular portion, integral with the other two, and folded upon and adhesively secured, transversely, to the outside surface of one of said other two portions, thereby to provide a second compartment, said third rectangular portion being free for a portion of the length of its longitudinal edge from the other portion to which it is transversely secured, and said free edge portion providing a sealing flap for said second compartment.

4. As a new article of manufacture, a two compartment envelope formed from a single sheet or blank, the latter having a rectangular body portion, with opposite side flaps projecting therefrom and adapted to overlap when folded toward each other along the edges of said body portion, thereby to form a large compartment between said body portion and one of said flaps and a smaller compartment between said overlapping side flaps, a longitudinal seam for the back wall of said large compartment being formed by adhesively securing said overlapping flaps together along the free edge of one of them, said seam having a gap therein, to form an entrance to said smaller compartment, and the edge of one of said overlapping side flaps, for the length of said gap, being gummed to provide a sealing closure for said entrance gap to said smaller compartment.

Dated this 18th day of December, 1922.

EDWARD W. BURKE.
